Fig. 6.

Fig. 1.

Fig. 5.

Fig. 1 is a top perspective view of a bobbin winder for a sewing machine showing my new design;
 Fig. 2 is a bottom plan view;
 Fig. 3 is a left side elevation view;
 Fig. 4 is a top plan view;
 Fig. 5 is a right side elevational view;
 Fig. 6 is a front elevational view;
 Fig. 7 is a rear elevational view;
 Fig. 8 is a front-head end perspective view of a sewing machine with the bobbin winder in place; and
 Fig. 9 is a fragmentary front-standard end perspective view of a sewing machine with the bobbin winder in place.
 The broken lines in Figs. 8 and 9 are for illustrative purposes only.

I claim:
 The ornamental design for a bobbin winder for sewing machines, substantially as shown and described.
